UNITED STATES PATENT OFFICE.

RICHARD F. DOW, OF HARTFORD, CONNECTICUT, ASSIGNOR TO PRATT & WHITNEY COMPANY, OF HARTFORD, CONNECTICUT, A CORPORATION OF NEW JERSEY.

MACHINE FOR TAPER-FORMING.

1,233,994.

Specification of Letters Patent. Patented July 17, 1917.

Application filed March 27, 1916. Serial No. 86,843.

To all whom it may concern:

Be it known that I, RICHARD F. Dow, a citizen of the United States, residing at Hartford, in the county of Hartford and State of Connecticut, have invented certain new and useful Improvements in Machines for Taper-Forming, of which the following is a specification.

This invention relates to machines for taper-forming. A machine involving the invention can be used with advantage in various arts; for example it can be employed to act either on metal or on wood. Among the principal objects of the invention are the provision of an apparatus of the kind set forth which is effective in action and by which a taper can be rapidly and accurately formed on a blank or anything else for that matter. There are other features of novelty and advantage which with the foregoing will be stated at length in the following description of that form of embodiment which I have selected for illustration in the drawings accompanying and forming part of the present specification. I do not limit myself to this disclosure; I may depart therefrom in several respects within the scope of the invention defined by the claims following said description.

Referring to said drawings:

Figure 1 is an elevation from the front side of the principal parts of a machine embodying the invention.

Fig. 2 is a longitudinal central section of the spindle, bearing means therefor, and certain of its adjuncts, the intermediate portion of the spindle being removed.

Fig. 3 is a transverse section on the line 3—3 of Fig. 2, looking in the direction of the arrow.

Fig. 4 is a transverse sectional view on the line 4—4 of Fig. 1, looking in the direction of the arrow applied to said line.

Fig. 5 is an elevation as seen from the right in Fig. 1. of the spindle, a swiveled yoke supporting the spindle and certain co-operating devices hereinafter described.

Fig. 6 is a side elevation of a portion of the taper bar and certain co-operating elements hereinafter more particularly described.

Like characters refer to like parts throughout the several views, which it will be noticed are on different scales.

5 The different parts of the machine may be

supported by any suitable framework; that shown includes in its organization the base or bed 2 having on its upper side suitable ways for supporting the carriage or slide 3 for reciprocation in a horizontal direction. 60 In the present case the blank or article to be tapered and the taper bar are both carried by this carriage or slide, although this may not be so in all instances. The carriage may be operated in any desirable manner. 65 While the action may be automatic it is shown as being manual. As illustrated the carriage has on its under side the rack 4 suitably rigidly attached thereto (Figs. 1 and 5) with which the pinion 6 meshes. 70 This pinion may be rigid with the shaft 7 supported by the base or bed 2 and provided with some suitable means for turning it, the crank 8 being shown to obtain this particular function. On the turning of the 75 crank in one direction the carriage 3 is advanced toward the right in Fig. 1, whereas on opposite movement of the crank the carriage is retracted through the agency of the intervening described parts. I might state 80 at this time that on the advance movement of the carriage the cutter hereinafter described acts on the blank or work.

On the upper side of the carriage 3 and extending longitudinally thereof are the 85 companion flanges 9 and 10 adapted to receive between them the pillow member 11, the blank 12 being adapted to lie in the pillow member 11. This pillow member snugly fits between the flanges 9 and 10, and one of 90 its sides is cut away to provide for the inner ends of one or more screws as 13 tapped through the flange 10 to engage against the work or blank 12 to force the same solidly against the inner wall of the pillow or blank 95. Supporting member 11. The flanges 9 and 10 with the co-operating devices just described constitute a suitable vise for holding the work or blank 12 in a solid and substantial manner, the work and the working- 100 holding means, as shown, extending longitudinally of the carriage 3 and necessarily in the line of movement of the latter. For additional security the work may be overhung by clamping plates 14 fastened suitably 105 as by screws 15 to the upper flat edges of said flanges 9 and 10. This is merely one convenient way of holding the work.

As already observed, the work is a taper cut and to secure this particular result a 110

suitable templet or taper bar as 16 may be provided, this taper bar being inclined upwardly toward the tail end of the machine. It is stationary on the carriage or slide 3. 5 As shown it is fastened to the laterally extending base portion 9' of the vise member 9. This taper bar is merely one of several types of templets or patterns which answers the necessary purpose. As will be clear others 10 of a radically different character could be utilized. There may be in fact instances where the work at zones would require reliefs and the active surface of the templet or taper bar 16 can be shaped to secure this 15 16 particular condition. The taper bar and the work are therefore, in the organization illustrated both rigid with the carriage 3, but as will be obvious, this may not be necessary in all cases, although it is of advantage.

20 To cut the work, a cutter or blade as 17 may be provided. This cutter or blade 17 as shown is sustained by a spindle as 18. The body of the spindle is hollow and its inner end may receive the plug 19 suitably rigidly 25 connected with the hollow body as by the pin 20. This plug 19 is shown supported for rotation in an opening in the pendent bearing 21 of the arm 22 constituting a suitable carrier for the spindle. The spindle 30 between its ends is sustained by a second bearing 23 also depending from the carrier or arm 22. Said carrier 22 is further provided with a fork 24, the branches of which have bearings 25 and 26 to receive the spindle 35 18. In the present instance the spindle is rotative. As shown the elongated bearing 26 is pivotally supported as by the pivot 27 between the upstanding branches of the yoke 28 swiveled as by the pivot 29 (Fig. 5) 40 to the upper side of the base or bed 2. In view of this condition the spindle carrier 22 is susceptible of universal movement turning about a horizontal axis (the pivot 27) and a vertical axis presented by the pivot 45 29. For rotating the spindle 18 any suitable means may be provided, said spindle having fastened to it in some suitable way the pulley or band wheel 30 (Fig. 1) shown for this purpose. As represented the pulley is located between the branches of the fork 24. 50 Its operating belt is not, however, shown.

During work the carrier 22 or a suitable member associated therewith is in contact with the taper bar or templet 16, and this 55 contact can be secured in any desirable manner as by means of the hand lever 31 fulcrumed to the bracket 32 (Fig. 1) rising from and rigid with the bed 2, said hand lever 31 between its fulcrum and handle 60 33 being pivotally connected as at 34 to the spindle carrier 22 near the free end thereof. By pressing therefore, downwardly on the handle 33 a pin or equivalent member 65 connected with the spindle carrier can be held in engagement with said taper bar. To

elevate the carrier 22 and therefore to move said pin (hereinafter described) away from the taper bar any suitable means may be provided. For this purpose I have shown the spring 35 connected as by one or more 70 screws or bolts 36 to the head end of the base 2 and also connected to a band or collar as 37 fastened to the carrier 22 adjacent the free end thereof. The constant tendency of this spring is to swing the arm or carrier 22 upwardly, the operator by holding the lever 33 down maintaining the said carrier in operative relation. When the attendant frees the lever, the spring 35 will at once lift the carrier 22 so as to carry the same out of engagement with the taper bar as will herein-after more particularly appear.

The cutter or knife 17 in the present case revolves by and on the rotation of the spindle 18 which carries it. In addition to this 85 revoluble movement of the cutter or knife, it has a progressive advance which in the present case is outward in order to form a channel or to finish a previously formed channel to the requisite contour, which in 90 the present case is tapered. Said knife or cutter may be advanced in any desirable manner, although the means shown for this purpose is satisfactory. I should also state that the hollow body of the spindle 18 at or 95 near the inner end thereof and adjacent the plug 19 is furnished with diametrically opposite slots 38 which receive the shank of the cutter or knife 17 for sliding movement radially of the spindle 18. Extending longitudinally of said spindle is the rod 39 movable longitudinally of the spindle for advancing and retracting the cutter or knife 17. This rod 39 is provided at its inner end 100 with a tubular head as 40 constituting a part thereof and connected thereto in any desirable manner as by the pin 41. This head 40 as shown is provided with the diagonal or oblique extension 42, fitting the correspondingly formed notch or slot 43 (Fig. 2) in 105 the shank of the cutter or knife 17. From this it will be clear that if the rod 39 be advanced relatively to the spindle 18, the knife or cutter 17 will be correspondingly advanced owing to the action of the oblique 110 extension 42 acting against one of the walls of the slot or notch 43. It might be stated that in the showing the advance of the rod 39 is toward the left in Fig. 2, and it will, therefore, be clear that in this same view 115 the cutter on its advance moves downward. On retraction of the rod 39 the knife or cutter 17 is correspondingly retracted.

As may be clear the advance of the cutter or knife 17 is secured primarily through the 120 templet or taper bar 16. It will be clear that in the construction shown the cutter or knife 17 on its advance moves toward the work. Connected with the free end of the spindle carrier 22 is a bracket 44 to slidably receive 125

the pin 45 a member suitable for coöperation with the taper bar 16. As illustrated the pin 45 moves in a direction at right angles or approximately so to the axis of rotation of the spindle 18.

The motion of the pin 45 secured by the advance of the taper bar 16 can be transferred to the rod 39 in any desirable manner. The means shown for this purpose and now to be described are satisfactory. The upper end of the pin 45 is adapted to engage the rock arm 46 connected to and extending inwardly from the rock shaft 47, the crank 48 depending from said rock shaft and having jointed to it the elongated rod or link 49 connected at its forward end (Figs. 1 and 6) to the crank arm 50 supported by the rock shaft 51 sustained by arms 52 rising from the elongated bearing 26 (Fig. 2). To said shaft 51 between the arms 52 is the shifting element 53 forked to fit the rabbet 54 (Fig. 2) in the sleeve 55. Through said sleeve 55 the tube 56 extends, the sleeve being cupped to receive the enlarged portion 57 of the tube 56 which as illustrated is disposed at its inner end in the bore 58 in the outer end of the body of the spindle 18. The tube 56 in the present case is slidable in said bore. The rod 39 is surrounded in said bore 58 by the coiled spring 59, one end of which bears against the tube 56 and the other against the bottom of the bore 58. While the tube 56 is slidable in the bore 58 it is rigid with said rod 39 (as will hereinafter appear), the consequence being that the spring 59 by acting against the tube normally or when the parts are at rest, holds the tube 56 and therefore the rod 39 yieldingly in their retracted positions as shown practically in Fig. 2. The bushing 60 surrounds the outer portion of the tube 56 and its reduced extension is received in the reduced part of the sleeve 55, said bushing being rigid in the bearing 26. The extreme forward end of the tube 56 is threaded to receive the nut 61 through a perforation in the outer closed head of which the rod 39 extends, stop collars as 62 being fastened as by pinning to said rods at opposite sides of and engaging the head of said nut 61. From this it will be clear that not only the rod 39 and tube 56 are connected together for movement as one, but that the rod 39 may be adjusted longitudinally of the spindle 18 by the turning of the nut 61. The bushing 60 is non-rotative in the bearing 26 and the tube 56 as shown is keyed in the spindle 18, so that when the nut 61 is turned to longitudinally adjust the rod 39 in the manner aforesaid, the tube 56 will not be rotated. The shifting element 53 is forked to straddle the reduced part of the sleeve 55, the branches of the fork abutting against the head or enlarged portion of said sleeve, the consequence being that as the pin 45 is elevated as will hereinafter appear, the fork 53

is advanced or moved toward the left in Fig. 2 so as to effect the movement through the intermediate parts of the rod 39 toward the left in Fig. 2, thereby causing the obliquely disposed extension 42 to impart an outward thrust to the cutter or knife 17.

The action of the machine is as follows: It will be supposed that the slide 3 is in its retracted position, that the knife or cutter 17 is in its retracted position and that the arm or carrier 22 has been swung down through the manipulation of the lever 31 to carry the pin 45 against the forward end of the taper bar 16 and to position the knife or cutter 17 in the previously formed groove 80 in the work or blank 12. It will also be supposed that the spindle 18 is being rotated so as to cause a revolution of the cutter 17. In Fig. 1 the slide 3 has just commenced its advancing movement in the direction of the arrow in Fig. 1 through the operation of the hand crank 8. As the carriage advances and as the spindle 18 rotates, the cutter will be caused to revolve and its cutting end will follow the transverse radius of the channel or groove in the work 12. As the slide 3 and work 12 advance, the taper bar 16 moving with them, the rise of the taper bar or the active surface thereof will elevate the pin 45 and therefore through the intermediate described parts advance the cutter 17 so that the groove or channel in the work 12 will be tapered longitudinally, the groove being gradually deepened as the work and taper bar advance with the slide. At the conclusion of the cutting operation the attendant will release the lever 33, so that the spring 35 can automatically lift the carrier 22 to thereby move the cutter 17 away from the work 12 and the pin or finger 45 away from the taper bar at which point the carriage or slide 3 can be retracted through the agency of the crank 8, and when said slide is in its backward position, the work can be taken off and a new piece put in its stead at which time the operation described will be repeated.

As the rod 39 is advanced through the inward swinging of the forked shifting element 53 and sleeve 55, the spring 59 is compressed so that when the advancing movement is concluded the spring as soon as the pin 45 is freed from the taper bar 16 can by acting against the tube 56 return the latter and the rod 9 and associated parts including the cutter 17 and pin 45 to the initial positions thereof.

As will be obvious I do not limit myself to any specific construction for carrying the invention into effect. I might note for example as one of many obvious departures that while the taper of the bar 16 is upward and outward, this is an inconsequential matter, for the taper might be oppositely reversed. I have already mentioned the fact

that the taper bar may be of such nature as to secure at one or more intervals in the work a relief or reliefs. In like manner while the taper bar 16 has its incline straight, this may not in all instances be required. I also wish to allude to the fact that the channel in the stock is not only tapered longitudinally but laterally.

What I claim is:

1. In a machine of the class described, the combination of a revoluble cutter, work supporting means, the cutter being adapted to operate upon the work, means for effecting the relative movement of the cutter and the work in the direction of the axis of revolution of the cutter, a templet, and a member supported independently of the cutter and adapted to traverse the active face of the templet, and means for transferring the effect of said member to the cutter to move the cutter toward the work on the relative movement of the cutter and the work.
2. In a machine of the class described, the combination of a revoluble cutter, work supporting means, the cutter being adapted to operate upon the work, means for effecting the relative movement of the cutter and the work in the direction of the axis of revolution of the cutter, and means involving a taper bar stationary with respect to the work, for moving the cutter toward the work during the relative movement of the work and the cutter.
3. In a machine of the class described, the combination of a rotary spindle, a cutter supported by said spindle for movement transversely thereof, bearings sustaining the spindle, the cutter being situated between the bearings, means for supporting work to be acted on by the cutter, means for effecting the relative movement of the work and the spindle in the direction of the axis of rotation of the spindle, and means for effecting the movement of the cutter during the entire relative movement of the spindle and the work to thus taper the work throughout its length.
4. In a machine of the class described, the combination of a rotary spindle, a cutter supported by said spindle for movement transversely thereof, bearings sustaining the spindle, the cutter being situated between the bearings, means for supporting work to be acted on by the cutter, means for effecting the relative movement of the work and the spindle in the direction of the axis of rotation of the spindle, and means involving a templet for effecting the movement of the cutter toward the work during said entire relative movement of the work and the spindle to thus taper the work throughout its entire length.
5. In a machine of the class described, the combination of a rotary spindle, a cutter

supported by said spindle for turning movement therewith, work supporting means, the cutter being adapted to operate upon the work, means for effecting the relative movement of the spindle and the work in the direction of the axis of rotation of the spindle, and means involving a templet stationary with respect to the work for moving the cutter toward the work during the relative movement of the work and the spindle.

70

6. In a machine of the class described, a rotary spindle provided with a cutter movably supported thereby, a carrier for the spindle mounted for reciprocation, and means for moving said cutter transversely of the spindle during its rotation and during the complete advancing movement of the carrier.

75

7. In a machine of the class described, a rotary spindle provided with a cutter movable transversely thereof, means for moving the cutter with respect to the spindle, a movably mounted carrier for the spindle, spring means acting against the carrier to move the spindle to inoperative position, and manually operable means for operating the carrier in opposition to said spring means.

85

8. In a machine of the class described, a swiveled yoke, an arm pivotally supported by said yoke, a rotary spindle supported by the arm, a cutter carried by and movable transversely of the spindle, and means for effecting the movement of the cutter with respect to the spindle.

90

9. In a machine of the class described, the combination of a reciprocatory slide provided with work holding means and with a taper bar, a rotary spindle provided with a cutter movable relatively thereto, the cutter being adapted to act on the work during the reciprocation of the slide, a pin to be engaged and operated by the taper bar on the advance movement of the slide, and means actuated by said pin for effecting the movement of said cutter toward the work on the advance of said slide.

95

10. In a machine of the class described, the combination of a reciprocatory slide provided with work holding means and with a taper bar, a rotary spindle provided with a cutter movable relatively thereto, the cutter being adapted to act on the work during the reciprocation of the slide, a pin to be engaged and operated by the taper bar on the advance movement of the slide, a rod inclosed by the spindle and provided with means for operating the cutter with respect to the spindle, and means actuated by said pin for advancing said rod to effect the corresponding movement of the cutter toward the work.

100

11. In a machine of the class described, the combination of a reciprocatory slide provided with work holding means and with

110

115

120

125

130

a taper bar, a rotary spindle furnished with a cutter movable relatively thereto, the cutter being adapted to act on the work during the reciprocation of the slide, a pin to be engaged and operated by the taper bar on the advance movement of the slide, a rod inclosed by the spindle and provided with means for advancing and retracting the cutter, spring means acting against the rod to retract the same, and means actuated by said pin for effecting the advance of said rod and therefore the movement of the cutter toward the work on the advance of the slide.

12. In a machine of the class described, a rotary spindle provided with a trans-

versely movable cutter, a rod inclosed by the spindle and provided with an oblique extension, the shank of the cutter having a correspondingly shaped slot to receive said extension, spring means for retracting the rod and thereby the cutter, and independent means for advancing the rod and thereby the cutter with respect to the spindle.

In testimony whereof I affix my signature in presence of two witnesses.

RICHARD F. DOW.
